(57) **CLAIM**

The ornamental design for a handle, as shown and described.

DESCRIPTION

FIG. 1 is a front perspective view of a handle showing my new design;

FIG. 2 is a rear perspective view thereof;

FIG. 3 is a front elevational view thereof;

FIG. 4 is top plan view thereof, a view from the bottom being a mirror image;

FIG. 5 is a rear elevational view thereof;

FIG. 6 is a left side view thereof, a view from the right side being a mirror image;

FIG. 7 is a front perspective view of handle showing an alternative embodiment of my new design; and,

FIG. 8 is a rear perspective view of the sides of the handle not shown in FIG. 7.
